UNITED STATES PATENT OFFICE

2,325,203

TRANSFER DEVICE

Oswald G. Hayes, North Hempsted, N. Y., assignor to Socony-Vacuum Oil Company, Incorporated, New York, N. Y., a corporation of New York

Application April 16, 1942, Serial No. 439,180

5 Claims. (Cl. 214—17)

This invention relates to means for transferring solids from one zone to another while substantially isolating the atmospheres of said zones and substantially avoiding crushing of the transferred solids.

In a number of industrial processes it is desirable to feed solids, in forms varying from fine powders to lumps and granules of definite or irregular shape, from a source space to another space of an environment in respects such as temperature, pressure and gases present. To prevent intermingling of the atmospheres of the two spaces to a material extent, it is necessary to interpose some mechanical means often referred to as a "valve" which may or may not have a feature of accurate flow control. Such devices as star wheels, paired gate valves and others have been proposed and extensively used for various purposes of this nature. Where crushing of the solids is not important as in feeding coal to a retort or ore to a furnace, known mechanisms have been fairly satisfactory.

However, in a number of instances, it is desirable to maintain the integrity of the individual particles to a substantial extent. A noteworthy example of this is the continuous catalytic cracking of hydrocarbon oils wherein a solid catalyst comprising pellets of clay or a synthetic alumina-silica composition are fed to a chamber through which the oil is passed in vapor form. The cracking operation rapidly deposits a carbonaceous contaminant on the surface of the pellets which inhibits their cracking efficiency to such an extent that the catalyst becomes commercially impractical in a relatively short time, in some operations about 6 to 8 minutes. The catalyst is then purged of hydrocarbon liquids and vapors by the action of an inert gas such as steam and/or vacuum, whereupon it is regenerated by burning off the carbon with preheated air and returned to the cracking chamber after another purging operation. Since the catalyst is usually conveyed through a space open to the atmosphere between cracking and regenerating chambers, it will be seen that a number of transfer devices of the type to which the invention relates must be included in a complete plant. The pellets are formed to an optimum size to present a large area for contact with hydrocarbon vapors while permitting relatively free flow through the catalytic mass. Crushing of the pellets is to be avoided as full as possible.

The present invention contemplates a transfer device or valve adapted to the above purposes which permits transfer of pellets or other solid

forms between spaces isolated from each other while avoiding crushing to a substantial extent. The invention is further characterized by the reduction of attrition at relatively moving surfaces by handling the solids in such manner that fine particles are restrained from entering between relatively moving parts of the device.

These together with other objects and advantages of the invention will be apparent from the description below of preferred embodiments illustrated in the annexed drawing wherein:

Figure 1 is a longitudinal section through a device embodying novel aspects of the invention;

Figure 2 is a view partially diagrammatic and partially in section of a possible modification of the feed end thereof;

Figure 3 is a diagrammatic showing of another form in which the invention may be embodied;

Figure 4 is a partial section on line 4—4 of Figure 3;

Figure 5 is a diagrammatic view illustrating a third form of the invention which may also be regarded as a development of the device of Figure 3 in an advanced position; and

Figure 6 is a detail showing of a modification of the device of Figure 1 which is also adaptable to Figures 3 and 4.

The device of Figure 1 is constructed to transfer solids from a hopper 10 to a closed vessel 11 through a conduit indicated generally at 12. The conduit and associated elements form, in effect, two series of chambers arranged for relative motion of the series with respect to each other and adapted for communication of each chamber of one series alternately with each of two adjacent chambers of the opposing series. In the embodiment of Figure 1 there is a stationary series typified by chamber 13 formed in the walls of the conduit 12. The other series is defined by the walls of the conduit and reciprocating elements fitted therein such as the blocks 14 and 15. Preferably the blocks defining the tops and/or bottoms of the chambers of the reciprocating series move together, being joined as by rod 16 and operated by a connecting rod 17 driven by a suitable source of power, not shown.

The upper surface of each of the blocks 14 and 15, the bottom of chamber 13 and all other surfaces defining the lower boundary of chambers of either series are sloped in the direction of discharge to a substantial extent. Under the effect of movement of the parts of the apparatus, solids will normally discharge into a com-

municating space of lower level over a polished surface of a slope less than the extreme angle of repose of the solid particles; but a slope at least equal to that angle is preferably given to these surfaces to insure adequate discharge.

As the reciprocating series is moved through a plurality of cycles it will be seen that material will be discharged from the upper surface of block 14 into the chamber 13, completely clearing that surface if the material thereon is not in excess of the quantity which will be held by chamber 13, considering the angle of the upper surface of material so discharged to chamber 13. Assuming that the quantity above block 14 has not been excessive, the upward stroke of the reciprocating series will permit the edge of block 14 nearest chamber 13 to contact the wall of conduit 12 without crushing and/or shearing of solid particles.

As the upward stroke continues, the lower edge of block 14 will clear the bottom of chamber 13 after the top has been closed to the conduit and the chamber 13 will discharge into the conduit below block 14. On the succeeding downward stroke the lower edge of the wall defining the bottom of chamber 13 will pass the block 14 in the same manner as the block cleared in the upward stroke. Thus the solids may pass to and from a number (one or more) of chambers similar to 13 in the wall of the conduit in progressing downwardly by gravity without crushing and with a minimum of attrition due to solid particles between relatively moving parts.

The final discharge from the conduit 12 to the enclosed vessel 11 may be direct through the conduit from the lowermost chamber similar to 13, but is preferably from a final reciprocating chamber above block 15. At the low point of the downward stroke, block 15 moves out of contact with the walls of conduit 12 and discharges the material thereabove into the vessel 11. By reason of the shape of its top portion, block 15 will normally re-enter conduit 12 in proper relation on the upward stroke, but it is preferable to provide guides to reduce vibration effects, such as the flanges 18 engaging slots in the sides of block 15.

The device is capable of transferring solid material downwardly through the conduit against a considerable pressure differential between vessel 11 and hopper 10. In a number of instances, however, it is desirable to inhibit the passage of gases from the vessel 11 upwardly through the conduit 12. For example, where vessel 11 is a catalytic cracking vessel, the hydrocarbon vapors may be prevented from contacting catalyst in the conduit to cause preliminary cracking accompanied by deposition of carbon at excessive rates due to long period of contact; and the vapors may be prevented from passing out to the atmosphere by the provision of an inlet 19 for steam or other inert gas. When block 15 moves down to open communication between vessel 11 and conduit 12, the inlet 19 is uncovered permitting entrance of steam under a pressure somewhat in excess of the pressure in vessel 11, thus preventing flow of gases from vessel 11 into conduit 12.

The steam inlet 19 may also be used to provide purging medium to displace gases included in the voids of the mass of solid particles. Such purging medium, such as steam, will move upwardly through the device gradually accomplishing the desired result before exhausting through hopper 10. This effect may, of course, be augmented by

additional steam supply along the length of the device or a flow of such purging medium may be established across a chamber of either series; for example, chamber 13.

5 In order to provide for a quantity of solids above block 14 not in excess of that which can be discharged into chamber 13, there is provided means to deliver to the upper end of conduit 12 a limited quantity of solids from hopper 10. In 10 the embodiment of Figure 1, this is accomplished by the provision of a star wheel type of valve 20 receiving solids from the throat 21 of the hopper 10. In order to avoid crushing of particles by the valve 20, the vanes of the star wheel are 15 so proportioned to the walls of the valve that there is considerable clearance between relatively moving parts, preferably on the order of the greatest dimension of the particles or somewhat greater. The valve 20 is thus merely a restraining device wherein "arching" of the mass of particles prevents any flow between vane and wall. Very satisfactory operation is obtained by intermittent rotation of the star wheel coordinated with motion of rod 17 in such manner that particles are restrained from dropping to the upper 20 part of conduit 12.

A very advantageous alternative to the valve 30 20 is shown in Figure 2. Where the solids are elevated from a lower level to enter the top of vessel 11, a bucket conveyor 22 or the like may be coordinated with the stroke of connecting rod 17 in such manner that solids will not be discharged onto block 14 at the time it is approaching the position to close chamber 13.

In Figures 3, 4 and 5 are shown modifications 40 of the invention wherein relative motion of the parts is in a horizontal direction. In Figure 3 a core member 23 and an annular member 24 are mounted for relative rotary motion. Reference is made to Figure 5 as a development of the device of Figure 3 in an advanced position. Formed in the core 23 are a pair of chambers 25 having 45 sloping bottom walls communicating with chambers 26 in the annular member. At a level below chambers 25 and adapted at their upper parts to communicate with the lower parts of chambers 26 are a pair of chambers 27 formed in the core 50 23 at an angular distance of 90° from chambers 25. Still lower are chambers 28 in the annular member.

The upper chambers 25 are fed in a controlled manner, as described in connection with Figures 55 1 and 2, with solid particles which pass downwardly through the series of chambers as members 23 and 24 are caused to have relative rotary motion with respect to each other.

Figure 5, in addition to being a development of 60 Figure 3, may be regarded as illustrating diagrammatically a form of the invention wherein two flat members having chambers 25, 26, and 27 are caused to reciprocate with respect to each other.

65 Where operation of the restraining means is not completely effective or where for other reasons, there is a tendency for finely divided material to enter between relatively moving surfaces, a wiper or brush 29 may be provided as shown in Figure 6 as a modification of the structure of Figure 1. The wiper 29 may, if desired, be of sufficient strength to support a column of solids and it is then possible to dispense with the separate but coordinated restraining means of Figures 1 and 2. As shown in Figure 6, a stiff brush is provided

and arranged with a space below to permit solids to fall from below the brush to chamber 13, but any particles adhering to the wall of conduit 12, as by reason of static charges, are swept off and carried upwardly on the upward stroke.

Various modifications within the scope of the invention will be immediately apparent. For example, the reciprocating member of Figure 1 may be a core in a device generally similar to that of Figures 3 and 4 with the chambers of the core and annular member rearranged to suit or formed in continuous circles.

I claim:

1. In a device of the class described, wall means defining a substantially vertical conduit having at least one chamber in communication therewith throughout the length of said chamber and formed with a bottom portion open to and sloping toward said conduit, a plurality of blocks closely fitting inside said wall means, means to reciprocate said blocks together longitudinally of said conduit, one of said blocks being associated with said chamber with its upper surface sloping toward said chamber and adapted to alternately place said chamber in communication with said conduit above and below said block as it reciprocates, one of said blocks being disposed for reciprocation below said chamber and adapted to alternately close and open the lower end of said conduit by motion into and out of said conduit, means to admit fluid to said conduit above said last named block when the lower end of said conduit is open and means to control the flow of solid matter to the upper end of said conduit.

2. In a device of the class described, wall means defining a substantially vertical conduit having at least one chamber in communication therewith throughout the length of said chamber and formed with a bottom portion open to and sloping toward said conduit, a plurality of blocks closely fitting inside said wall means, means to reciprocate said blocks together longitudinally of said conduit, one of said blocks being associated with said chamber with its upper surface sloping toward said chamber and adapted to alternately place said chamber in communication with said conduit above and below said block as it reciprocates, and means to control the flow of solid matter to the upper end of said conduit.

3. In a device of the class described, wall means defining a substantially vertical conduit having at least one chamber in communication therewith throughout the length of said chamber and formed with a bottom portion open to and sloping toward said conduit, a plurality of blocks closely fitting inside said wall means, means to

reciprocate said blocks together longitudinally of said conduit, one of said blocks being associated with said chamber with its upper surface sloping toward said chamber and adapted to alternately place said chamber in communication with said conduit above and below said block as it reciprocates, one of said blocks being disposed for reciprocation below said chamber and adapted to alternately close and open the lower end of said conduit by motion into and out of said conduit.

4. In a device of the class described, wall means defining a substantially vertical conduit having at least one chamber in communication therewith throughout the length of said chamber and formed with a bottom portion open to and sloping toward said conduit, a plurality of blocks closely fitting inside said wall means, means to reciprocate said blocks together longitudinally of said conduit, one of said blocks being associated with said chamber with its upper surface sloping toward said chamber and adapted to alternately place said chamber in communication with said conduit above and below said block as it reciprocates, one of said blocks being disposed for reciprocation below said chamber and adapted to alternately close and open the lower end of said conduit by motion into and out of said conduit, means to admit fluid to said conduit above said last named block when the lower end of said conduit is open, a wiper extending along the lower edge of the upper surface of said block associated with said chamber and means to control the flow of solid matter to the upper end of said conduit.

5. In a device of the class described, wall means defining a substantially vertical conduit having at least one chamber in communication therewith throughout the length of said chamber and formed with a bottom portion open to and sloping toward said conduit, a plurality of blocks closely fitting inside said wall means, means to reciprocate said blocks together longitudinally of said conduit, one of said blocks being associated with said chamber with its upper surface sloping toward said chamber and adapted to alternately place said chamber in communication with said conduit above and below said block as it reciprocates, one of said blocks being disposed for reciprocation below said chamber and adapted to alternately close and open the lower end of said conduit by motion into and out of said conduit and means to admit fluid to said conduit above said last named block when the lower end of said conduit is open.

OSWALD G. HAYES.
